(57) **CLAIM**

The ornamental design for a RG cable connector, as shown and described.

DESCRIPTION

FIG. 1 is front, top right perspective view of an RG cable connector, according to the invention;

FIG. 2 is front, top right perspective view of an RG cable connector, according to the invention shown in an alternate view;

FIG. 3 is a front elevational view thereof;

FIG. 4 is a back elevational view thereof;

FIG. 5 is a right elevational view with the left elevational view being a mirror image thereof;

FIG. 6 is a top plan view thereof; and,

FIG. 7 is a bottom plan thereof.

The broken lines shown represent unclaimed subject matter and form no part of the claimed design.
